UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A COR-
PORATION OF MICHIGAN.

TRAIN-CONTROL SYSTEM.

Application filed June 12, 1925. Serial No. 36,628.

This invention relates to the control of the operation of railway trains by means of high-frequency oscillating currents propagated in or impressed upon the rails at intervals along 5 the track by means of transformers and circuits preferably associated with the signal system of the trackway, and its object is to provide a system of this character whereby one of two audible signals is caused to sound 10 in the locomotive cab whenever the locomotive passes over a track section in which a current is propagated, the signal depending upon the wave length of the current in the track and the current being of one wave 15 length when the next or second track section in advance is occupied and of another wave length when the three blocks in advance are unoccupied.

The train control system hereinafter described is shown in the drawings associated with a signal system of the three lamp "approach light" type connected to rails divided into blocks, but it is to be understood that our invention is not limited to use in connection 20 with a signal system of this character but may be used with any desired type of signal system or may be used without signal lamps.

This invention consists in a system of control stations each embodying an electron or 30 vacuum tube containing a filament which receives a current of about ten volts, which tube is connected in an oscillating circuit containing fixed and variable condensers and induction coils and means to modify the circuit so that it will transmit currents of two different wave lengths to the track, one when the track section either the next or the second in advance is occupied and another when the next three sections or blocks in advance are 35 unoccupied, and in connection with such track-way stations, it comprises an installation upon a locomotive for picking up magnetic lines of force corresponding to said wave lengths, and embodying audible signals 40 for indicating such currents in the track, and in a normally inoperative brake mechanism which is caused to operate when a predetermined one of said currents is propagated in the track.

50 The invention also consists of thermo-junctions connected into the receiving circuits on the vehicle whereby the picked-up oscillating currents may be rectified, and a polar relay controlled by the thus rectified currents

and adapted to select the circuit between a 55 battery and one or the other of said audible signals according to the picked-up current.

It also consists in a normally closed circuit between a current source and an electro-pneumatic valve connected into the air brake 60 system of the vehicle, which circuit is opened when a predetermined one of the said currents is picked up, and a pair of forestalling keys, which, when both are depressed, provide a new energizing circuit for said electro-magnetic valve and thereby prevent the application 65 of the brakes.

It further consists of the details of construction illustrated in the accompanying drawings and particularly pointed out in the 70 claims.

In the drawings, Fig. 1 is a diagram of an installation mounted on a locomotive, the brake mechanism being shown in section. Fig. 2 is a diagram of a transmitting trans- 75 former, Fig. 3 shows three diagrams of track stations embodying both signal and control installations.

Similar reference characters refer to like parts throughout the several views. 80

The signal installations, with which our novel control installations are combined, embody lamp stands provided with three signal lamps, preferably green, yellow and red, which indicate how the track in advance is 85 occupied, the green lamp showing that the two blocks in advance are unoccupied, at which time the parts of the station are said to be in "clear" position; the yellow lamp showing that the second block in advance is 90 occupied at which time the parts of the station are said to be in "caution" position; and the red lamp showing that the next block in advance is occupied, at which time the parts of the station are said to be in "danger" position. The lamps are respectively termed 95 "clear", "caution" and "danger" lamps. The track illustrated is that of one of two parallel tracks, each of which is set apart for traffic in one direction which is considered to be from right to left in Fig. 3. The blocks and the stations therefor are lettered from A to D inclusive, and block A is supposed to be occupied. For this reason, the parts of station B are in "danger" position, those of block C in "caution" position, and those of block D in "clear" position.

Relays are shown in the drawings, each

provided with one or more armatures designated by small letters, and in the following description, the armatures will be designated by their respective letters following the numeral designating the relay to which they belong. Where the procedure is of advantage, a part of a station installation may be further designated by using the letter of its block or station together with the numeral of the part.

The rails 1 and 2 are divided into blocks by insulations 3 in the usual manner and adjacent the exit end of each block is a lamp stand 4 provided with red, yellow and green lamps. Adjacent each station and in part controlling it is a track relay 7 connected to the rails by wires 5 and 6. These relays are energized by track batteries 8 which connect to the rails by means of wires 9 and 10, resistances 11 being used to prevent damage to the batteries when the rails are short circuited by means of the axles of rolling stock.

At each station is a signal battery 12 which connects to its lamp stand by a common wire 13. The return circuits from the lamps are controlled by a polar-neutral relay 14 which is energized by current from the battery of the next station ahead coming in over wire 15. When no current comes over wire 15, relay 14 is de-energized and its armature *d* remains in its last position, for example, at its left hand position, in block B. If positive current comes over this wire, armature 14^a swings clockwise, as at block D. If negative current comes over the wire, the armature swings counter-clockwise, as at block C. No current passes to the signal lamps when relay 7 is energized and this relay remains energized until its block of track is occupied as will hereafter be explained. This results in great saving of battery current for there is no current used for the signal lamps at any station unless the block to which it is connected is occupied.

Referring now to Fig. 3, no current flows over wire 15^a to relay 14 of station B, block A being occupied by train T and the positions of the parts at station A being those at station D, where the normal circuit to the battery 12^D over wire 16^D, wire 25, armature 7^c, wire 26, armature 14^a and wire 21, is opened by dropped armature 7^e of de-energized relay 7. As block B is unoccupied, no current flows to the lamp-stand, at B as all the circuits from the lamps are opened by the relay 7, but if it were occupied and relay 7 de-energized, current would flow over common wire 13 to red lamp R and then over wire 17, armature 14^c, wire 20, armature 7^a and wire 21 to the battery. The red lamp indicates "danger" in the block ahead, that is, that such block is occupied.

As block B is unoccupied but block A is occupied, negative current flows to relay 14^c over wire 21, armature 14^b and 15^b and back

from relay 14^c over wires 16 and 25, armature 7^c, wire 26, armature 14^a and wire 13 to the battery. As block C is unoccupied, no current flows to the lamps at C', but if it were occupied, current would flow from the 70 battery over common wire 13 to yellow lamp Y, then back over wire 18, armature 14^d, wire 22, relay 14^c, wire 20, armature 7^a and wire 21 to the battery. The yellow lamp indicates "caution" in the block ahead, that is, that the second block ahead is occupied.

As blocks B and C are unoccupied, positive current flows over wire 13, armature 14^b and wire 15^c to relay 14^b and back over wires 16 and 25, armature 7^c, wire 26, armature 80 14^a and wire 21 back to the negative end of the battery, and as block D is occupied, current flows from battery 12^D over common wire 13 to green lamp G at D, thence back over wire 19, armature 14^d, wire 22, armature 14^c, wire 20, armature 7^a and wire 21 to the battery. The green lamp indicates "clear" in the block ahead, that is, that neither the next nor the second block in advance is occupied.

In this figure, the circle 24 indicates the transmission device for propagating high-frequency oscillating currents of different wave lengths in the rails. Current is conducted to this device by means of the wire 95 63 which connects to the wire 13 and returns over the wire 64 connected to the wire 20. It is therefore evident that no current flows to the transmitter unless the relay 7 is de-energized, that is, unless the block to which the transmitter is connected is occupied. This again makes for saving of battery current.

The current transmitter.

As indicated in Fig. 3, the wires 63 and 64 connect to a motor-generator 65 and to the filament 66 of a vacuum or audion tube 67, an adjustable resistance 68 being provided in the filament circuit to control the temperature of the filament. The wire 63 is also the conductor of the high voltage from one side of the motor-generator 65 to the grid coil 80, and the wire 73 from the other side of the motor-generator connects to the plate coil 74 110 which connects to the plate 75 by means of wire 76. This coil is shunted by the variable condenser 77 whereby the oscillations may be limited to a predetermined wave length and these oscillations are transmitted to the rails 115 1 and 2 by means of the wires 78 and 79 from the loading coil 81, the wires 78 and 79 preferably connecting to the wires 5 and 6. These oscillations are those which are transmitted 120 when the second block in advance is occupied, that is, are of the "danger" wave length. A condenser 82 is shown connected into the wire 78 to exclude the direct current of battery 8 connected to the same block with the transmitter.

105

110

115

120

125

130

The polar-neutral relay 83 is energized by current received from the second station in advance over wire 84, and the neutral armature 83^a (Fig. 2) connects the wire 85, which shunts the plate coil 74, to the polar armature 83^b which is swung clockwise by a positive current over wire 84, under which condition the additional condenser 86 and wire 88 are brought into the circuit, and is swung counterclockwise by a negative current over this wire, when the second condenser 87 and wire 89 are brought into this shunt circuit. The shunt circuit embodying the condenser 86 so influences this current transmitter that "clear" wave lengths are propagated in the rails, and the circuit embodying the condenser 87 causes oscillations of a third wave length, and while this particular current is not used to influence instrumentalities on the locomotives, its production prevents the propagation of "danger" current in the rails. For convenience, this current will be termed the "caution" current.

Referring now to station B, no control current passes to the rails because block B is not occupied and relay 7 is energized. But if it were occupied, current would pass over wires 13 and 63 to transmitter 24 and over wires 64 and 20, armature 7^a and wire 21 to the battery. No current passes to the rear over the wire 84^A from the station of block A as block A is occupied and the circuit to this wire is opened by armature 7^b of station A, so the relay 83^b is de-energized and the short circuit wire 76 carries all the current from the plate coil 74, resulting in the current of the shortest or "danger" wave length being propagated in the rails.

Connected to the wire 79, extending from the transmitter 24 to the rails, is a relay 90 which responds to these high-frequency currents, and attracts its armature *a*, closing a circuit to the slow-release relay 92, said circuit consisting of the wire 93, armature 90^a, wire 94, relay 92 and wire 95 to wire 63. The energized relay 92 attracts its armatures. As soon as the assumed train T leaves block B, relay 90 becomes de-energized, but relay 7 becomes energized, and a circuit to relay 92 over wires 13, 63 and 95 to the relay and wire 94, armature 92^b, wire 96, armature 7^a and wire 21 to the battery is closed, and it remains closed until its block is again occupied, when the first described circuit to this relay is again closed.

As stated before, no current passes to relay 14^B because block A is occupied. No current passes to lamp R of station B because block B is not occupied. No current passes to transmitter 24 of station B because this block is not occupied. Current passes from the negative end of battery 12^B over wire 21, armature 14^b, wire 15^B to relay 14 of station C, then over wires 16, 25, armature 7^c, wire 26, armature 14^a and wire 13 to the battery. This current causes the armature 14^d of station C to swing

counterclockwise and positive current to flow from the battery 12 of station C over wire 13, armature 14^b, wire 15^C to relay 14 of station D, wires 16 and 25, armature 7^e, wire 26, armature 14^a and wire 21 to the battery. This result in armature 14^d of station D swinging clockwise.

If block B were occupied and relay 7 there-of de-energized, current would flow to transmitter 24 and oscillating current would be propagated in the rails of that block. But no current would be received over wire 84^A by the relay 83^B because block A is occupied and its relay 7 de-energized, so that armature 83^a would not be attracted and the current transmitted would be of the short wave length to indicate danger. The distance from the connecting points of wires 5 and 6 at which a locomotive picks up current will be dependent upon the vacuum tube 67, but the distance and the time during which the locomotive occupies this energized track are sufficient for the current to affect the instrumentalities on the locomotive before the end of the block is reached.

Current to control relay 83 of block D flows from battery 12 of station B over wire 13, armature 14^a, wire 26, armature 7^e, wires 25^B, 16 and 28^C, armature 7^b of station C, wire 30^C, armature 92^b, wire 84^C to relay 83^B then over wire 29^D, armature 7^b, wires 28^D, 16, and 15^B, armature 14^b and wire 21 to the battery, causing armature 83^a of station D to be attracted to close the circuit to wire 85, and armature 83^b to swing counter-clockwise to prevent the production of the "danger" wave length.

It will be noticed that the current flows to relay 83^B over wire 84^C and back over wire 16. If block A were unoccupied, relay 14^B would be energized and current from battery 12^B would flow over wire 13, armature 14^b, wires 15^B, 16 and 28 to armature 7^b of station D, wire 29 to relay 83 and thence over wire 84^C, armature 92^b, wire 30, armature 7^b, wires 28, 16 and 25, armature 7^e of station B, wire 26, armature 14^a and wire 21 to the battery. This would cause armature 83^b of station D to swing clockwise, as shown in Fig. 2, resulting in oscillating current of predetermined wave length, differing from the "danger" current and the caution current, and designated as "clear" current hereinafter.

It will therefore be seen that when block A is occupied, and a train approaches from the right, a green lamp will be visible at the exit end of block E (not shown) and the track of block E (not shown) will receive "clear" control current. When the train occupies block D, a green lamp will again be visible at the exit end thereof and another or "caution" current will be propagated in the rails of that block near the exit end thereof. When the train enters block C, a yellow light becomes visible at the exit end thereof and "danger" current is propagated in the rails

at the exit end thereof. When the train enters block B, a red light becomes visible at the exit end of the block and "danger" current is propagated in the exit end of this block also.

- Should any transmitting mechanism fail to function, its relay 90 will not be energized, nor will the relay 92 so that the circuits which embody the wire 84 of that station will be 10 opened, resulting in "danger" current being propagated by the second station in the rear if its block is occupied. When relay 14 of any station fails to receive current, the next station in the rear propagates "danger" current 15 in its rails if its block is occupied. The character of the high-frequency current in the track depends therefore upon the condition of the next and of the second station in advance so that the engineer of a train running 20 on that track will be given "danger" notice two blocks in advance if there is anything wrong with any station.

The locomotive installation.

- 25 Mounted on the locomotive at an oblique angle to the rails and just in front of the leading axle of the locomotive where the lines of magnetic flux are strongest, are two collector coils 98 and 100, the former connected to 30 the thermo-junction heater current converter 99 and the latter to the converter 101. These converters may be of any desired type, and the circuits of these coils are tuned respectively to resonance with the "clear" and "danger" currents propagated in the rails, by the 35 adjustable condensers 102 and 103 respectively. The converters rectify the picked up current or flux and may be adjusted as desired, but in the present case it will be assumed 40 that the coil 98 picks up magnetic flux created by the "clear" current in the rails and the coil 100 the flux created by the "danger" current. It is also assumed that the currents are so rectified that the relay 105 is energized 45 by these rectified currents passing to it over wires 106 and 107 and that "clear" current in the rails causes the armature 105^a to swing clockwise, and "danger" current causes this armature to swing in the opposite direction. 50 No provision is made to detect the third or "caution" current.

- When "clear" current causes the armature 105^a to swing clockwise, current flows from the battery 109 over wire 110 and resistance 55 111, armature 105^a, wire 112, solenoid 113, wires 114, 115 and 116 to the battery. This energizes this solenoid and causes it to lift the valve 118 so that air under pressure may flow from the ordinary storage tank of the 60 air brake system through pipes 119 and 120 to the whistle 121 which will continue to sound so long and as often as relay 105 receives current, which occurs while the locomotive is traveling through each length of track carrying "clear" current. The signal

stops sounding as soon as the locomotive leaves this energized track. As the lengths of track which carries sufficient control current to cause the locomotive installations to operate are less than the lengths of the block, 70 the whistle 121 will sound at intervals only and so notify the engine crew that the locomotive is leaving the "clear" block.

The armature 105^a is normally in neutral position as shown, and current normally 75 passes from the battery over wire 110 and resistance 120, armature 108^a, wires 121 and 124 to relay 108 and over wires 125, 126, 127 and 116 to the battery, normally energizing this relay which attracts its armatures 108^a 80 and 108^b, the former closing its stick circuit and the other closing the circuit from wire 110, armature 108^b, wire 128, solenoid 117, and wires 115 and 116 to the battery. This energizes the solenoid 117 which causes the 85 valve 129 to close the passage between the pipes 119 and 138. The resistance of 111 and 120 may be equal but each is higher than the resistance of relay 108.

When armature 105^a swings counter-clockwise as explained above, relay 108 is short circuited, and the current flows from wire 110 over resistance 111, armature 105^a, wires 104, 126, 127 and 116 to the battery, the resistance of 111 being less than that of relay 108 90 and resistance 120 combined. This relay being short circuited, it drops its armatures and opens the circuit to solenoid 117, which releases the valve 129 and air flows from the pipe 119 to pipe 138, resulting in the sounding 95 of whistle 139 and normally in the application 100 of the brakes. This valve and its solenoid is usually termed an electro-pneumatic valve in this art.

Two forestalling keys 122 and 123 are provided so that as soon as the whistle 139 sounds, they may be depressed simultaneously by the engineer and fireman, to close an auxiliary circuit to relay 108 over wires 110, and 161, key 123, wire 162, key 122, wires 163 and 124, 110 which will supply current to this relay as soon as armature 105^a swings counterclockwise. But these keys must be depressed simultaneously and an accidental closing of one of them has no effect. As the relay 105 is 115 energized only during the short time the collector coils 98 and 100 are passing along charged rail sections, the time during which the valve 129 is open is not sufficient to cause the application of the brakes, provided the 120 engineer and fireman are both alert and depress their keys. As soon as solenoid 117 is energized and valve 129 is closed, the danger whistle ceases to sound.

When the solenoid 117 is de-energized, air 125 flows through the pipe 138 to the whistle 139 and to the check-valve body 140, lifting the valve 142 and passing through pipes 143, 144 and 145 to the control cylinders 146 and 147 and to the storage tank 148, which merely 130

accumulates air and permits of delayed movements of the pistons 149 and 150.

The piston 149 moves the valve 152 to close the normal passage between the train pipe 130 and the train valve 131 so that the engineer cannot supply air to the train pipe to prevent the setting of the brakes. But he can set his valve to exhaust the train line pipe. The check valve 153 will permit this upward flow 10 of air.

When the valve 158 is forced to its innermost position, it connects the small passage 154 (which is controlled by the needle valve 155 and is connected to the outside air by the 15 vent 156) to the space above the piston 157. When the parts are as shown in Fig. 1, the air pressure on both sides of this piston 157 is the same, and the passage 154 is cut off from the space above the piston 157 by the 20 valve 158 connected to the piston 150. But when the valve 158 permits the air above the piston 157 to escape through the vent 156, the pressure below this piston, being full train pipe pressure, will lift this piston and 25 with it the valve 159, permitting the escape of air from the train pipe through the restricted vent 160, which results in setting the brakes. This flow will be slow because of the tank 134 which holds air at the same 30 initial pressure and which must also escape through the vent 156.

All this time the whistle 139 is sounding and if the engineer and fireman are both alert, each can operate his forestalling key 35 to cause the electro-pneumatic valve to close. But unless the forestalling keys are depressed, air will continue to escape from the train pipe and result in the brakes being applied.

40 When the control keys are depressed and the solenoid 117 is energized to stop the flow of air from the pipe 119, the engineer may open his train valve 131 to permit full pressure air to flow into the train pipe which will 45 result in the valve 152 and piston 146 being pushed back to normal position, which is rendered possible by the escape of the air in the pipes 143, 144 and 145, cylinders 146 and 147 and tank 148 through the whistle 139, the 50 valve 142 being so formed as to permit a slow flow of air to the pipe 138. The new pressure in the train pipe 130 and its branch 132 also forces the valve 158 and piston 150 back to the position shown in Fig. 1.

55 Whenever therefore, the collector coil 100 passes along a properly energized zone where it picks up current of the proper wave length, the relay 105 will cause the valve 129 to admit high pressure air to the cylinders 146 and 60 147, which results in the application of the brakes unless forestalled by the proper use of the keys 122 and 123 which should be so placed that they cannot be operated by one man.

65 The details of construction and the ar-

rangements and positions of the various parts may all be changed by those skilled in the art without departing from the spirit of our invention as set forth in the following claims.

We claim:

1. In a train control system, a track divided into blocks, a train control station connected to the rails of each block and each embodying a current source and means for propagating high-frequency currents of different 70 wave lengths in the rails of the block to which it is connected, and means embodying conductors extending continuously from a control station to the current source of the second block in advance to determine the wave 75 lengths of such currents.

2. In a train control system, a track divided into blocks, signal and control installations connected to the rails at the exit end of each block, each signal installation embodying a current source and a group of electric signal lamps, said control installation embodying means for propagating high-frequency currents of different wave-lengths in the rails of its block, means influenced by a 80 vehicle in a block for causing the operation of the signal and control installations of that block, and means energized by the current source at the second installations in advance to determine the wave-length of the propa- 85 90 95 gated current.

3. In a train control system, a track divided into blocks, signal and control installations connected to the rails at the exit end of each block, each signal installation embodying a current source and a group of electric signal lamps, said control installation embodying means for propagating high-frequency currents of different wave-lengths in the rails of its block, means influenced by a 100 vehicle in a block for causing the operation of the signal and control installations of that block, and means energized by the current source at the second installations in advance to determine the wave-length of the propa- 105 110 115 gated current, and means energized by the current source at the next installations in advance to determine the signal lamp to receive current.

4. In a train control system, a track divided into blocks, a train control station connected to the rails of each block and embodying a current source and means for propagating high-frequency currents of different wave-lengths in the rails of each block, a 120 polar relay to determine the wave-lengths of said currents, conductors connecting said relay to the current source of the second station in advance, and means at said second station to determine the direction of current 125 passing to said relay.

5. In a train control system, a track divided into blocks, a signal and train control station connected to the rails of each block and embodying a current source, means for propa- 130

gating high-frequency currents of different wave-lengths in the rails of each block, and a group of electric signal lamps, a polar relay to determine the wave-lengths of said currents, a second polar relay to determine the signal lamp to receive current, conductors connecting said first named polar relay to the current source of the second station in advance, means at said second station to determine the direction of current passing to said relay, conductors connecting said second named polar relay to the current source of the next station in advance, and means at said next station to determine the signal lamp to receive current.

6. In a train control system, a track divided into blocks, a signal and train control station connected to the rails of each block and embodying a current source, means for propagating high-frequency currents of different wave-lengths in the rails of each block, and a group of electric signal lamps, a polar relay to determine the wave-lengths of said currents, a second polar relay to determine the signal lamp to receive current, conductors connecting said first named polar relay to the current source of the second station in advance, means at said second station to determine the direction of current passing to said relay, conductors connecting said second named polar relay to the current source of the next station in advance, and means at said next station to determine the signal lamp to receive current, and means influenced by a vehicle in a block to cause the functioning of

the propagating means and of the selected lamp.

7. In a train control system, a track divided into blocks a train control station connected to the rails of each block and embodying a current source and means for propagating high-frequency currents of different wave-lengths in the rails of each block, a polar relay to determine the wave-lengths of said currents, conductors connecting said relay to the current source of the second station in advance, and means at said second station to determine the direction of current passing to each relay, and means controlled by the high-frequency current propagating mechanism of the next station in advance to open and close the circuit to said polar relay.

8. In a train control system, a track divided into blocks, a train control station connected to the rails of each block and embodying a current source and means for propagating high-frequency currents of different wave-lengths in the rails of each block, a polar relay to determine the wave-lengths of said currents, conductors connecting said relay to the current source of the second station in advance, and means at said second station to determine the direction of current passing to said relay, a current source and a relay connected to the rails of each block at opposite ends thereof, and an armature of said relay for closing the circuit between the current source and the current propagating means.
